(57) **CLAIM**

The ornamental design for a crossbow bumper, as shown and described.

DESCRIPTION

FIG. 1 is a perspective view of a crossbow bumper, showing my new design;

FIG. 2 is a top thereof;

FIG. 3 is a bottom view thereof;

FIG. 4 is a back view thereof;

FIG. 5 is a front view thereof;

FIG. 6 is a left side view thereof; and,

FIG. 7 is a right side thereof.

The broken lines in the Figures represent unclaimed portions of the device and are for illustrative purposes only. The broken lines form no portion of the claimed design.

1 Claim, 1 Drawing Sheet(56)
